[57] CLAIM

The ornamental design for a gutter cleaning tool, as shown and described.

DESCRIPTION

FIG. 1 is a top perspective view of a gutter cleaning tool showing my new design;

FIG. 2 is a bottom perspective view thereof;

FIG. 3 is an end elevational view thereof;

FIG. 4 is an end elevational view as seen from the end opposite that shown in FIG. 3;

FIG. 5 is a bottom plan view thereof;

FIG. 6 is a side elevational view, the side not shown being a mirror image of the side shown; and

FIG. 7 is a top plan view thereof.

The handle is shown broken away in FIGS. 1, 2, 5, 6 and 7 to indicate indeterminate length.
